UNITED STATES PATENT OFFICE.

WILLIAM A. AUSTIN AND VICTOR J. SHEPARD, OF LIMA, OHIO, ASSIGNEES TO LIMA LOCOMOTIVE CORPORATION, OF LIMA, OHIO, A CORPORATION OF OHIO.

HOSE-STRAINER.

1,119,564.

Specification of Letters Patent.

Patented Dec. 1, 1914.

Application filed April 7, 1914. Serial No. 830,131.

To all whom it may concern:

Be it known that we, WILLIAM A. AUSTIN, residing at 415 South Cole street, and VICTOR J. SHEPARD, residing at 119 South Baxter street, Lima, county of Allen, and State of Ohio, both citizens of the United States, have invented certain new and useful Improvements in Hose-Strainers, fully described and represented in the following 10 specification and the accompanying drawings, forming a part of the same.

The present invention relates to a means of inserting a strainer in the hose-connection between an engine and tender, whereby 15 coarse impurities may be strained from the water and the straining-plate cleaned without any delay or difficulty whenever it becomes clogged, and without detaching any hose-joint.

20 The strainer is formed with a casing having two complementary chamber-sections with a strainer-plate inserted in the joint of the sections and means for clamping the sections together upon the strainer which permits their ready separation when it is desired to reach the strainer for cleaning the same. The strainer-casing is preferably inserted at the point where the hose is connected to the feed-pipe, as such pipe is fixed 25 rigidly upon the locomotive, and thus supports one section of the casing when the other section is removed for cleaning, the flexibility of the hose permitting such opening of the casing without detaching the hose 30 from any of its connections. The sections of the casing are preferably made with annular flanges beveled upon their outer sides so that a split clamp-ring with a beveled groove can be easily applied to press them 35 together, and can be readily removed therefrom when it is necessary to open the casing, thus avoiding the use of clamping bolts which necessitate the removal of many nuts every time the strainer is opened.

40 The invention will be understood by reference to the annexed drawing, in which—

Figure 1 is a longitudinal section of the strainer, on line 1—1 in Fig. 3, and Fig. 2 is an elevation of the end for the rigid pipe-connection. Fig. 3 is a side elevation of the split-clamp, and Fig. 4 a section of the same on line 4—4 in Fig. 3. Fig. 5 is a view of a part of the strainer upon double the scale of the other figures. Fig. 6 shows 45 the cotter in the bolt o.

The casing-sections *a* and *a'* are made of globular form and provided with nozzles at their opposite ends, the section *a* having an internally threaded nozzle *b* for connection with a metallic pipe *c*, and the section *a'* having an externally threaded nozzle *d* for connection with a hose-coupling *h*. The nozzle *b* has a supporting ear or ears *f* at one side which can be fitted over a stationary stud to hold that section of the casing 50 rigidly upon the locomotive, so as to resist the jars to which the casing is subject. The sections are provided with annular flanges *g*, *g'*, the former having upon its inner face an annular recess *e* to receive the strainer-plate *i*. The recess is proportioned to set the strainer flush with the inner side of the flange *g'*, and an annular packing *j* is fitted in the joint between the flanges *g*, *g'*, and thus presses equally upon the flange *g'* and 55 upon the edge of the strainer-plate, when the flanges are clamped together. The strainer-plate is jammed tightly in the recess. The flanges are beveled upon their outer sides, and a split clamp-ring *k*, *k'* is 60 formed with an inner groove *l* to fit upon such beveled sides. The sections of the clamp-ring are formed with a hinge-joint *m* at one side and slotted lug *n* and pivot-lug *n'* at the opposite side to which a hinge-bolt 65 *o* and nut *o'* are applied, as shown in Fig. 3, for pressing the clamp upon the strainer-flanges. A lock-nut *o* is shown outside the nut *o'* to hold it securely, and a cotter *c* is 70 shown outside of the nut *o* to prevent either of the nuts from getting loose, thus keeping the device constantly in an efficient and operative condition. A transverse notch *p* is 75 formed in the edge of the flanges *g*, *g'*, and a stud *q* is provided in one side of the groove 80 *l* to engage such notch and keep the split clamp from turning around upon the flanges and holding the nut *o'* in a predetermined position for unfastening.

Fig. 5 shows a strainer as a metal plate 85 perforated with numerous small holes adapted to intercept any coarse impurities suspended in the water, and the setting of such strainer-plate in a recess at the joint of the sections enables the packing *j* to 90 tightly close the joint of the sections and the joint of the strainer-plate therewith.

The spherical or enlarged form of the chamber-sections *a*, *a'* allows an area for the openings in the strainer-plate fully 95

equal to that of the hose or pipe with which the strainer is connected, and the means for pressing the sections of the strainer together permits their instant separation whenever necessary for the cleaning of the strainer, and without detaching the flexible hose-pipe or metallic pipe-connections. This obviates the breaking of pipe-joints and the disturbance of packings 5 in union-joints either upon the strainer-chambers or elsewhere, which not only involves loss of time but involves great wear of the joints and packings. The flexibility of the hose permits the separation of the 10 sections by merely bending the hose when the clamp k , k' is removed, which is effected by merely loosening the nut o' upon the bolt o , and the whole interior of the strainer may thus be cleaned without separating either of its sections from the 15 attached pipe.

The connections provided at the ends of the strainer-casing furnish a rigid support for the part a of the casing in which the 20 strainer-plate is jammed tightly so that it cannot become detached or lost when the strainer-sections are separated for cleaning. The split clamp-ring can in like manner be attached to such stationary part, as by the 25 chain shown at s in Fig. 1, so that when loosened from the flange of the strainer-sections it may not be lost if inadvertently left in the roundhouse where it would generally be taken off to clean the strainer. In such 30 cleaning operation, the engine-man first loosens the bolt o , and when the clamp-ring is removed from the strainer-sections it hangs upon the chain s attached to the section a , and as the dirt all accumulates upon 35 the outer side of the strainer-plate it can when the section a' is removed, be swabbed off without removing it from its casing.

The provision of the lug f upon the section a allows the ready application of the 40 strainer to the stationary stud upon the locomotive. The jointed clamp-ring k' permits the rapid separation of the strainer-sections for cleaning the strainer-plate, and the connection of the strainer-plate and the 45 clamp-ring with the stationary section a precludes the possibility of losing either of such parts at such times as the engine is out of service, and disconnected entirely from the tender.

50 Having thus set forth the nature of the invention what is claimed herein is:

1. In a hose-strainer, the combination, with two hemi-spherical chamber-sections provided one with a screw-connection for a rigid iron pipe and with a supporting ear 60 to hold such section upon the locomotive, and the other section provided with a union-coupling for a hose, of annular flanges at the joint of the sections having their outer sides beveled as set forth, and a packing applied to such joint, a clamp having two parts hinged together and provided with a groove to engage the beveled sides of the flanges, and a pivoted bolt and nut for pressing the clamp-parts upon the flanges, whereby one section is held rigidly when in use, and the flexibility of the hose permits the other section to be separated therefrom for access to the interior of the coupling. 65

2. The combination, with two strainer-sections for a locomotive and tender connection, such sections having flanges at the joint, of a lug upon one of the sections for attachment to the locomotive thereby holding such section rigidly, a clamp for 70 pressing the flanges detachably together, and a flexible connection between the said clamp and the said rigid section, permitting the attachment and detachment of the clamp without risk of loss. 75

3. In a hose-strainer, the combination, with two hemi-spherical chamber-sections provided one with a screw-connection for a rigid iron pipe and with a supporting ear to hold such section upon the locomotive, and the other section provided with a union-coupling for a hose, of annular flanges at the joint of the sections having their outer sides beveled as set forth, a packing applied to such joint, a clamp having two parts hinged together and provided with a groove to engage the beveled sides of the flanges, a pivoted bolt and nut for pressing the clamp-parts upon the flanges, and a flexible connection between 80 the said clamp and the section having the supporting ear, whereby the clamp may be secured on the flanges or detached, without 85 risk of loss. 90

In testimony whereof we have hereunto 95 set our hands in the presence of two subscribing witnesses.

WILLIAM A. AUSTIN.
VICTOR J. SHEPARD.
